UNITED STATES PATENT OFFICE.

JOSEPHI ROTHSCHILD, OF NEW YORK, N. Y.

DESIGN FOR A HAND-STAMP.

SPECIFICATION forming part of Design No. 29,469, dated October 11, 1898.

Application filed September 12, 1898. Serial No. 690,810. Term of patent 14 years.

To all whom it may concern:

Be it known that I, JOSEPH ROTHSCHILD, of the city of New York, borough of Manhattan, in the county and State of New York, have invented and produced a new and original Design for a Hand-Stamp, of which the following is a full, clear, and exact description.

Reference is to be had to the accompanying drawings, forming a part of this specification, in which similar characters of reference indicate corresponding parts in both the figures.

Figure 1 is a perspective view of a hand-stamp, showing my design; and Fig. 2 is a plan view of the same.

The design consists of a base or body A,

from which depends the character-strip B, a handle C extending upward from the middle of the base or body, said handle having a flattened portion C' in a plane approximately 20 parallel to the inner face of the base-block A.

The leading feature of the design consists of the handle surmounting the base or body and having a plane surface at one side.

I claim—

The design for a hand-stamp herein shown and described.

JOSEPHI ROTHSCHILD.

Witnesses:

ISAAC B. OWENS,
JNO. M. RITTER.
